UNITED STATES PATENT OFFICE

2,460,100

ADJUSTABLE TRUSS

Frank G. McCord, Atlanta, Ga.

Application December 2, 1946, Serial No. 713,399

2 Claims. (Cl. 128—95)

1

This invention relates to improvements in trusses for hernia or, as it is commonly known, rupture, and has for one of its objects the provision of an adjustable truss that can be set to exert pressure in the locality on the wearer's body providing the most comfort and relief.

Other adjustable trusses have been placed in use but none has the simple operation of the truss designed in accordance with the invention. The trusses now in use for double ruptures consist of two steels or two bands passing around both sides of the body to carry the front pads, of which there are usually two in number on the front of the body.

An important object of this invention, therefore, is to provide a truss using only a single steel, passing around one side of the body only, to support two pads on the front of the body for a double rupture. The use of a single steel for a single pad is well known in this art, but it is believed that the use of a single steel to support two pads at the front of the body for a double rupture is an advance over the use of a single steel for the single rupture type of truss.

With the above and other objects and advantages in view, the invention consists of the novel details of construction, arrangement and combination of parts more fully hereinafter described, claimed and illustrated in the accompanying drawing in which:

Figure 1 is an elevational plan view of a double truss embodying the invention, with the pads shown in dotted lines;

Figure 2 is an elevational front view of a pad partly broken away, showing the means for attaching the pad to truss wire frame in dotted lines;

Figure 3 is an elevational plan view of a double type truss in place on the human body;

Figure 4 is the same of a single type truss;

Figure 5 is a detail showing a side elevational view of one end of the truss on an enlarged scale, and with parts broken away, illustrating the means for attaching pads to the truss.

Figure 6 is a horizontal sectional view on the line 6—6 of Figure 5;

Figure 7 is a vertical view on the line 7—7 of Figure 6, showing the sleeve in position to provide one arc of movement of the pad attaching means;

Figure 8 is the same as Figure 7, showing another arc of movement of the pad attaching means; and

Figure 9 is a perspective view of the sleeve for controlling the swing of the pad.

2

Referring more in detail to the drawing, the reference numeral 10 designates the substantially U-shaped truss wire which, as shown in Figures 3 and 4, is provided with a covering 11 of rubber or other suitable material.

One end of the wire is threaded at 12 to receive the pad 13 which rests on the back of the wearer's body, and the other end is threaded at 14 for a greater distance than at 12, to receive 10 the pads 15 and 15' which rest on the front of the wearer's body.

Each pad is provided with plates 16 and 17 respectively which are joined at their inner central longitudinal edges by the internally threaded 15 boss 18, and each plate has extended projections 19 at its outermost ends to more firmly seat the plates in the pad after fasteners for securing the pads to the plates have passed through the openings 20 in the plates.

20 The boss 18 of each pad is threaded onto its respective end of the wire 10 until the pad 13 rests comfortably on the wearer's body, and the pads 15 and 15' are properly located as to the 25 hernia of the wearer. To retain the pads in their position on the wire 10, there is provided for each pad the sleeve 21, which is loosely mounted on the wire 10. The sleeves are provided with opposed tapered slots 22 at the end nearest the pads which receive the ends of the plates 16 and 17 30 therein, and a set screw 23 is provided in the sleeve 21, which retains the pad in adjusted longitudinal position, but permits the pad to swing in a small arc on the wire 10. By adjusting the sleeve, the arc can be controlled as shown in 35 Figures 7 and 8.

In Figure 3, there is shown the double type of truss, as applied to the representation of the human body, as shown at 24, and in Figure 4, there is shown the single type of truss which 40 merely eliminates the use of the foremost pad 15 in its use. Thus the truss can be used as a single or double type truss, as desired by the wearer thereof.

45 This particular type of truss eliminates the use of any strap or other devices to hold the pads in position on the wearer's body, and will remain in place regardless of the movement of the wearer's body, the pads swinging slightly on the wire to prevent the pads digging into the wearer's 50 body at each movement thereof.

It is believed that from the foregoing description, the operation and construction of the invention will be apparent to those skilled in the art, and it is also to be understood that changes 55 in the minor details of construction, arrange-

ment and combination of parts may be resorted to, provided they fall within the spirit of the invention and the scope of the appended claims.

Having thus described the invention, what is claimed as new and desired to be secured by Letters Patent is:

1. In a truss, the combination which comprises a substantially U-shaped spring truss wire having threaded ends, a plate threaded on each of the ends of said wire for rocking movement thereon, each of said plates being adapted to hold a truss pad, and means also threaded on each of said threaded ends of the wire and having a slot therein to receive its complementary plate for limiting the rocking movement of the plate on the wire. 15

2. In a truss, the combination which comprises a substantially U-shaped truss wire having threaded ends, a plate having an internally threaded centrally-disposed boss integral there- 20

with and threaded on each of the ends of the wire for rocking movement thereon, and an internally threaded sleeve on each of the ends of the wire having opposed tapered slots therein, said sleeves being threaded on the ends of said wire, and so positioned thereon that the slots receive the ends of the plates to limit the rocking movement of said plates.
